UNITED STATES PATENT OFFICE

JOHN SCHADE, OF HOLYOKE, MASSACHUSETTS, ASSIGNOR TO NATIONAL BLANK BOOK COMPANY, OF HOLYOKE, MASSACHUSETTS, A CORPORATION OF MASSACHUSETTS

BOOSTER FOR LOOSE-LEAF RING BOOKS

Application filed November 29, 1929. Serial No. 410,391.

This invention relates to loose leaf books of the kind known as ring binders in which curved prong members are carried by flat metal strips hingedly connected at their centers and confined along their outer edges within a resilient plate, so that the prongs are opened and closed with a spring action.

But the present invention specifically has reference to what are known as "boosters" that are manipulated to open the prongs and that are located at the ends of the binder, the object of the invention being to so pivot the booster directly to the ends of the prong-carrying leaves, that they cannot become accidentally disassembled, are positive in their operation, and add little to the cost of the binder.

In the accompanying drawings—

Figure 1 is a broken top view of a binder equipped with the improved booster.

Figure 2 is a bottom view of such binder.

Figures 3 and 4 are sections at line 3—3 of Figure 2, and showing respectively the positions of parts before and after the booster 25 has been operated.

Figure 5 is an end view of the structure shown at Figure 1 with the prongs omitted, and

Figure 6 is a detail perspective of the booster.

Similar numerals of reference denote like parts in the several figures of the drawing.

1 is the cover plate of the binder made of spring-metal and having its side edges bent inwardly to form pockets 2 within which the hinged prong-carrying leaves 3 are housed in the usual manner, and 4 are the prong members.

The leaves 3 are extended from the ends of the binder and their outer lateral extremities have inwardly projecting hooks 5 which provide notches 6 for the purpose presently to be explained.

The booster comprises an upstanding thumb or finger piece 7 and a lower inwardly extending triangular part 8 which is the actual booster member, and the lateral edges of the booster intermediate the parts 7 and 8 are notched as shown at 9, and prior to the assembly of the leaves 3 within the pockets 2,

the notches 6 and 9 are interengaged so as to provide a pivotal relation between the booster and the leaves, and after such assembly the part 8 will extend beneath the leaves with the apex of said part immediately below the leaves at their line of hinging as clearly shown at Figure 3.

When the part 7 is forced outwardly the part 8 will be thrown upwardly against the leaves and will cause them to spring into the position shown at Figure 4 and this will open the prongs 4.

There is nothing new in the construction of the ring binder shown, nor is it new to provide boosters which operate in the manner above described, but the invention resides solely in the manner of hinging the booster.

What is claimed is:—

1. In a loose leaf ring binder comprising a resilient plate, prong-carrying hinged leaves confined within said plate and having extensions beyond the ends of said plate, inwardly projecting hooks formed on said extensions, and a booster having an upstanding part and an inwardly extending bottom part and provided with notches at the sides intermediate said parts, said notches being interengaged with said hooks.

2. In a loose leaf ring binder comprising a resilient plate, hinged prong-carrying leaves confined within said plate and having notched extensions beyond the ends of said plate, a booster having an upstanding part and an inwardly extending bottom part that underlies said leaves at their line of hinging, the side edges of said booster immediately above said bottom part having notches that are interengaged with the notches in said extensions.

3. In a loose leaf structure comprising a spring plate, a pair of notched prong-carrying leaves pivoted together and confined within said plate, a booster having notches at opposite side edges which coact with notches in the inner side edges of the leaves adjacent the ends thereof, whereby the booster is held in pivotal relation to said leaves.

In testimony whereof I affix my signature hereto.

JOHN SCHADE.
